UNITED STATES PATENT OFFICE.

BENJAMIN SKIDMORE, JR., AND EDWARD F. McCARTHY, OF CHICAGO, ILLINOIS,
ASSIGNORS TO VACUUM MACHINERY CO., A CORPORATION OF WISCONSIN.

COMBINED ASPIRATOR AND FORCE-PUMP.

1,361,191.

Specification of Letters Patent. Patented Dec. 7, 1920.

Application filed April 20, 1918. Serial No. 229,671.

To all whom it may concern:

Be it known that we, BENJAMIN SKIDMORE, JR., and EDWARD F. McCARTHY, citizens of the United States, residing at Chicago, in the county of Cook and State of Illinois, have invented certain new and useful Improvements in Combined Aspirators and Force-Pumps, of which the following is a specification.

- 10 This invention relates to improvements in combined aspirator and force pump adapted to produce and maintain a vacuum in a chamber or passage by entrainment or suction of the fluid therefrom.
- 15 A further object is to provide improved means for separating the gaseous fluid from the liquid, the gaseous fluid being delivered to a chamber or receptacle in which the aspirator is arranged, while the liquid is delivered to a force pump and by means of which pump, the liquid is discharged or conveyed to the point of use.

To the attainment of these ends and the accomplishment of other new and useful objects as will appear, the invention consists in the features of novelty in substantially the construction, combination and arrangement of the several parts hereinafter more fully described and claimed and shown in 30 the accompanying drawings illustrating this invention and in which;

Figure 1 is a view partly in vertical section and partly in elevation of an improved apparatus of this character, constructed in accordance with the principles of this invention.

Fig. 2 is a view similar to Fig. 1 of a modified form of the invention.

Referring more particularly to the drawings, the numeral 10 designates generally a chamber or receptacle which is supported in any suitable manner such as by means of legs 11, and arranged within the receptacle preferably at a point adjacent the bottom thereof, is an aspirator or suction creating device. The aspirator comprises preferably spaced disks 12, 13, which are separated from each other by means of upright partitions 14, and the parts are secured together in any suitable manner, such as by means of suitable fastening devices. Two of these partitions 14 are preferably provided and are arranged diametrically opposite each other, and this aspirator is connected with a shaft 15 in any

suitable manner so as to rotate therewith and 55 the shaft and aspirator may be supported by means of a suitable bearing comprising a support 16 and a collar 17 secured to the shaft and between which collar and support suitable anti-friction balls or rollers 18 are 60 arranged. The shaft is rotated by means of a suitable motor 19 mounted upon a suitable support 20 and a suitable flexible connection 21 is provided and forms a connection between the shaft 15 and the motor 65 shaft.

Depending from the aspirator is a tubular element 22 which rotates in a suitable bearing 23 and extends through the bottom of the chamber or receptacle 10. A suitable 70 packing 24 may be provided to form a fluid tight joint and the tubular element 22 has communication with the end 25 of an inlet pipe 26, through which pipe 26 the gaseous fluid is entrained from a tank or receptacle 75 27 by means of the aspirator. The suction created in the tank or receptacle 27 is manifested in the inlet pipe 28 and which pipe communicates with the chamber or passage-way in which it is desired to create a suction. 80

A check valve 29 may be provided in the pipe 26 so as to prevent the liquid 30 in the tank or receptacle 10 from flowing back into the pipe 26 when the aspirator is not in operation, and the aspirator is maintained submerged in the liquid 30. Arranged concentrically with the aspirator are upright members or baffles 31, any number of which may be provided and are for the purpose of breaking up or preventing the liquid 30 from 90 swirling in the chamber 10. If desired a suitable overflow may be provided which leads from the tank or receptacle 10 and a clean-out plug or valve 33 may also be provided in the bottom of the receptacle. Leading from 95 the receptacle 10 above the liquid level therein is an outlet 34 for the air or fluid which is delivered into the tank by the aspirator above the liquid level.

Connected with the shaft 15 is a force 100 pump, preferably of the centrifugal type and designated generally by the reference numeral 35 and which force pump has an inlet opening 36 connected with which is a pipe 37 leading from the tank or receptacle 105 27, preferably the bottom thereof.

In the form of the invention shown in Fig. 1, the pump is preferably arranged at

a point above the aspirator and a suitable packing 38 may be provided for preventing the liquid 30 from entering the pump. The pump is provided with an outlet pipe 39 which preferably leads to the outside of the tank or receptacle 10 and is provided with a check valve 40. With this form of the invention, and when the aspirator is started, a suction will be created in the pipe 26, 10 which suction is manifested in the tank or receptacle 27 and also the passage 28 to entrain or draw the fluid through the passage 28 into the tank or receptacle 27. At the same time the pump 35 will also draw air 15 from the tank 27, but as the fluid passes into the tank or receptacle, the liquid and fluid will be separated, the liquid gravitating to the bottom of the tank to flow through the pipe 37 to the pump 35 to be discharged 20 through the outlet pipe 39, and as the liquid flows through this pipe 37, any air or fluid which has accumulated or has been drawn into the pump 35 will find its way back through the pipe 37 and through the liquid 25 passing through the pipe into the tank or receptacle 27. This fluid will commingle with the fluid already in the tank or receptacle 27 and will be drawn therewith through the pipe 26 by the aspirator into the chamber 30 10 and the uncondensed fluid will pass through the liquid to the top of the chamber 10 from where it will pass through the outlet 34.

In the form of the invention shown in Fig. 2, the aspirator is arranged in a tank or chamber 41 which is superposed above another chamber 42, the two chambers being closed to each other and out of communication. In this form of the invention, the 40 shaft 15 of the aspirator projects through the bottom of the chamber 41 into the chamber 42 as at 43 and connected with this shaft 43 preferably adjacent the chamber 42 are blades 44 of a force pump 45 preferably of the centrifugal type, arranged adjacent the bottom of the receptacle 42 and having an inlet opening 46. Leading from the pump 45 is a discharge passage or pipe 47 which extends to the outside of the receptacle 42, 50 and may be provided with a check valve 48. The depending tubular element 49 which is connected with the aspirator revolves in a suitable housing 50 and which housing supports a bearing 51 through which the shaft 43 passes and the housing 50, together with the tubular element 49 are of an internal diameter considerably greater than the diameter of the shaft 43. Leading from the housing 50 is a pipe 52, which is bent to 55 form a goose neck 53, which extends into the tank or chamber 41 so that the upper portion of the bend thereof normally stands above the level of the liquid 30 in the tank or chamber 41. The free extremity 54 of this pipe 55 terminates within the tank or

chamber 42 and a check valve 55 may be provided for closing the end of the pipe.

The tank or chamber 42 may be provided with a cleanout or draw-off plug 56 and an inlet pipe 57 communicates with the tank 70 or chamber 42 and which inlet is connected with the chamber or passage in which it is desired to create a suction and an overflow 58 leads from the tank or chamber 41 and an outlet 59 also leads therefrom and through 75 which outlet the air or fluid which is delivered into the tank or receptacle 41 and accumulates above the liquid level therein, may pass.

With this form of the invention, it will be 80 manifest that when the aspirator is operated and assuming that there is no liquid in the tank or chamber 42, a suction will be created in the tank or chamber 42 through the pipe 52 and housing 50, and this suction 85 will be manifested in the passage 57. The liquid and fluid which is drawn into the tank or chamber 42 through this pipe 57 will be separated and the liquid will gravitate to the bottom of the tank or receptacle 90 42 while the fluid will be drawn by the aspirator through the pipe 52 and delivered into the tank or chamber 41. The inlet of the pipe 52 is always maintained above the liquid level in the tank or chamber 42, and the liquid will accumulate in the latter until it rises above the inlet opening 46 of the pump 45, at which time, the pump 45 will be primed and the liquid will be discharged by the pump through the pipe 47 past the 100 valve 48 and conveyed to the point of use. Thus it will be seen that the pump will discharge the liquid from the tank or chamber 42 whenever any of the liquid accumulates therein.

By the provision of the goose neck 53, it will be manifest that the pipe 52 will be prevented from siphoning the liquid 30 from the tank or chamber 41 when the aspirator is not in operation.

What is claimed as new is:

1. The combination of a chamber containing liquid, a rotary suction producing device submerged in the liquid within the chamber, a rotary pump, means for operating the suction creating device and pump, there being a suction passage through which gaseous fluid is drawn by the suction creating device, an outlet leading from the pump and through which outlet the liquid is discharged, and provisions for separating the liquid and gaseous fluid whereby they will be delivered directly and respectively to the pump and suction creating device.

2. The combination of a chamber containing liquid, a rotary suction creating device submerged in the liquid within the chamber, a pump, means for operating the suction creating device and pump, there being a suction passage through which gase- 130

ous fluid is drawn by the suction creating device, an outlet leading from the pump and through which outlet the liquid is discharged, and means disposed between the 5 pump and suction creating device for separating the liquid from the gaseous fluid whereby the liquid will be delivered directly to the pump and the gaseous fluid will be delivered to the suction creating device, 10 each independently with respect to each other.

3. The combination of a chamber containing liquid, a rotary suction creating device submerged in the liquid within the 15 chamber, a pump, means for actuating the suction creating device and pump, there being a passage through which gaseous fluid is drawn by the suction creating device, said passage embodying a separating chamber 20 in which the liquid is separated from the gaseous fluid, said suction creating device and pump both having independent communication with the chamber whereby the liquid will be delivered directly to the pump 25 and the gaseous fluid will be delivered directly to the suction creating device, each independently with respect to the other, and a discharge outlet for the pump.

4. The combination of a chamber containing liquid, a rotary suction creating device submerged in the liquid within the chamber, a pump, means for actuating the suction creating device and pump, there being a passage through which gaseous fluid is 30 drawn by the suction creating device, said passage embodying a separating chamber in which the gaseous fluid is separated from the liquid, said suction creating device and pump both having independent communication 35 with the chamber whereby the liquid will be delivered directly to the pump and the gaseous fluid will be delivered directly to the suction creating device, each independently with respect to the other, a discharge outlet for the pump, said suction 40 creating device being submerged, and an operating shaft common to the suction device and pump.

5. The combination of a chamber containing liquid, a rotary suction creating device submerged in the liquid within the chamber, a pump, means for actuating the suction creating device and pump, there being a passage through which gaseous fluid 45 and liquid are drawn by the suction creating device, said passage embodying a separating chamber, the inlet of the suction creating device having communication with said separating chamber above the liquid level in the 50 separating chamber; the inlet of said pump also having communication with said separating chamber, whereby the suction creating device will receive the gaseous fluid from the separating chamber after the liquid has

been separated therefrom, and a discharge 65 outlet leading from the said pump.

6. The combination of a chamber containing liquid, a rotary suction creating device submerged in the liquid within the chamber, a pump also within the chamber, 70 the inlet of the pump being disposed above the liquid level in the chamber, there being a passage through which liquid and gaseous fluid are drawn by the suction creating device, said passage embodying a separating 75 chamber, the inlet of the said suction creating device and pump both having communication with the chamber independently of each other, the inlet of the suction creating device being disposed above the liquid level 80 in the said separating chamber, means for operating the pump and suction creating device, and a discharge outlet leading from the pump to the outside of the first said chamber.

85 7. The combination of a chamber containing liquid, a rotary suction creating device submerged in the liquid within the chamber, a pump also within the chamber, the inlet of the pump being disposed above the liquid level in the chamber, there being a passage through which liquid and gaseous fluid are drawn by the suction creating device, said passage embodying a separating chamber, the inlets of the said suction creating device 90 and pump both having communication with the chamber independently of each other, the inlet of the suction creating device being disposed above the liquid level in the said separating chamber, means for operating the pump and suction creating device, and a discharge outlet leading from the pump to the outside of the first said chamber, the said operating means embodying a shaft common to the suction creating 95 device and pump, said suction creating device and pump being superposed.

100 8. The combination of a chamber containing liquid, a rotary suction creating device submerged in the liquid within the chamber, a pump also within the chamber, the inlet of the pump being disposed above the liquid level in the chamber, there being a passage through which liquid and gaseous fluid are drawn by the suction creating device, said passage embodying a separating 105 chamber, the inlets of the said suction creating device and pump both having communication with the chamber independently of each other, liquid from said separating 110 chamber being supplied to the pump through the inlet thereof by gravity.

115 In testimony whereof we have signed our names to this specification on this 16th day of April, A. D. 1918.

BENJAMIN SKIDMORE, JR.
EDWARD F. McCARTHY.
